W. C. RASTETTER

COLLAPSIBLE CHAIR

Filed Nov. 17, 1924

William C. Rastetter INVENTOR

BY

A. G. Burns ATTORNEY

UNITED STATES PATENT OFFICE.

WILLIAM C. RASTETTER, OF FORT WAYNE, INDIANA.

COLLAPSIBLE CHAIR.

Application filed November 17, 1924. Serial No. 750,370.

This invention relates to improvements in collapsible chairs, and the object thereof is to provide a chair with a main frame extending in a flat plane, and folding legs 5 for its support, and with a folding seat having supported relation with the frame and legs in such manner that the chair structure will be braced rigidly when in position for use. And another object is to provide 10 a collapsible chair, the folding parts of which are so connected together and arranged as to admit of their folding flatwise into the plane of the main frame of the chair.

15 These objects are accomplished by the construction illustrated in the accompanying drawings, in which:—

Fig. 1 is a side elevation of the structure embodying the invention;

20 Fig. 2 is a front elevation projected from Fig. 1; and

Fig. 3 is a bottom plan view of the seat, and parts with which it is connected.

The characters appearing in the description 25 refer to parts shown in the drawings and designated thereon by corresponding characters.

The invention comprises a frame 1 having parallel legs 2 spaced apart and connected 30 with a cross-piece 3 near their lower ends at the front thereof. A pair of folding legs 4 are pivoted respectively at their upper ends to the corresponding legs 2 of the frame adjacent the inner sides thereof, and said legs are connected together by a transverse 35 rod 5.

In the upper part of the frame is secured a swinging frame 6 having pendant arms 7 pivotally secured respectively to the corresponding legs 2 as indicated by 8, the lower ends of each pendant arm having a longitudinal slot 9 therein through which the transverse rod 5 extends and has limited upward movement therein so that the spread 45 between the folding legs and the frame is correspondingly limited by the swinging frame. The pendant arms 7 are connected together by a transverse bar 10, and a series of slats 11, vertically disposed, are secured 50 to said bar and to the top of the frame 6 to form the back-rest of the chair. A seat 12 having at its rear end a pair of brackets 13 has pivotal connection with the swinging frame 6, each bracket being secured to the

corresponding pendant arm 7 by a pivot 14 55 so that the seat swings upon a horizontal axis in said swinging frame.

A U-shaped shackle 15 having rearwardly extending arms 16 is mounted upon the pivots 17 in the legs 2 upon which the folding legs 4 swing, and each arm 16 of the shackle is connected at its rear end by means of a pivot 18 with the corresponding bracket 13 on the seat so that forward and backward movement of the seat in the main 60 frame when the seat is in position for use is prevented. The rear ends of the arms 16 of the shackle bear against the forward edges of the corresponding pendant arms 7 when the seat is in position for use, while said 65 seat rests upon the tops of the folding legs 4 by which downward movement of the seat is stopped.

In utilizing the invention, the folding legs serve to prop the main frame in position 70 for use and also their upper ends function as a fulcrum support for the seat, while the swinging frame limits the backward swing of the folding legs and also supports the rear end of the seat. The brackets 13 on 75 the seat and the arms 16 of the yoke function as a toggle connection between the swinging frame and the legs of the supporting frame, and thus when the seat is raised, the pendant arms of the swinging frame 80 are drawn by the toggle connection into folded position in the main frame, and the folding legs are actuated by the swinging frame. Thus, when the seat is raised to its folded position the swinging frame and the 85 folding legs are likewise moved.

What I claim is:—

1. In a collapsible chair, a main frame having legs spaced apart; a swinging frame pivotally supported in the upper part of 90 the main frame and having slotted pendant arms; a pair of folding legs pivoted at their upper ends respectively in the main frame adjacent the corresponding legs thereof and having a transverse rod connecting 95 them together at a point approximately midway between their ends which rod extends through the slots of said pendant arms; a folding seat having pivotal connection at its rear end with said swinging frame and bearing support on the tops of 100 the folding legs when in position for use; and a shackle having pivotal support in the 105

- main frame and with the rear end of the seat forward of the pivotal connection of said seat and swinging frame.
2. In a collapsible chair, a main frame having spaced legs; a back-rest pivotally supported in the upper part of the frame and having slotted pendant arms; a pair of folding legs pivoted at their upper ends in the frame and having sliding connection 10 with the pendant arms; a folding seat having pivotal connection at its rear end with said back-rest and bearing-support on the tops of the folding legs when in position for use; and a shackle having pivotal support in the frame at a point aligned with the pivotal connection for the folding legs and with 15 said seat adjacent the rear end thereof, said seat and shackle forming a toggle connection between the frame and back-rest.
3. A collapsible chair including a frame having spaced legs; a pair of folding legs pivoted respectively at their upper ends to the corresponding legs of the frame; a back-rest pivoted at its upper end in the frame 20 and having limited sliding relation with the

folding legs at the lower extremities of said back-rest; a folding seat pivoted at its rear end to the back-rest; and a shackle having support in the frame on the pivotal connections of the folding legs and the legs of 30 the frame and also with said seat near the rear end thereof, said shackle and seat forming a toggle connection between the back-rest and the frame operable to actuate the back-rest.

4. A collapsible chair including a frame having spaced legs and a pair of folding legs in pivotal connection therewith, pendant arms pivoted in the frame; means in connection with the folding legs and the 40 pendant arms operable to limit outward swinging movement of said folding legs; toggle members having connected relation with said frame and swinging arms; and a folding seat in connection with said toggle members and having actuating relation therewith.

In testimony whereof I affix my signature.

WILLIAM C. RASTETTER.
